TABLE OR THE LIKE

Herbert Ritts, P.O. Box 64,336, Los Angeles 64, Calif.

Filed Jan. 21, 1963, Ser. No. 73,251

Term of patent 7 years

(Cl. D33—14)

FIGURE 1 is a perspective view of a table or the like showing my new design, a portion of the top thereof being broken away for convenience of illustration;

I claim:

The ornamental design for a table or the like, substantially as shown.
